UNITED STATES PATENT OFFICE.

HOMER NEFF TYSON, OF TELFORD, WASHINGTON.

POISON-BOTTLE STOPPER.

1,264,713.

Specification of Letters Patent.

Patented Apr. 30, 1918.

Application filed November 9, 1916. Serial No. 130,385.

To all whom it may concern:

Be it known that I, HOMER N. TYSON, a citizen of the United States, residing at Telford, in the county of Lincoln and State 5 of Washington, have invented certain useful Improvements in Poison-Bottle Stoppers, of which the following is a specification, reference being had therein to the accompanying drawing.

10 The invention relates to a stopper, and more particularly to poison indicators and stoppers for bottles.

The primary object of the invention is the provision of a device of this character 15 wherein a person on attempting to extract the stopper or cork from a container such as a bottle, or on attempting to dispense the contents therefrom will be warned of such contents, thus obviating the accidental taking or administering of the contents should 20 the same be of a poisonous or dangerous nature.

Another object of the invention is the provision of a device of this character wherein 25 the construction thereof will eliminate the accidental taking or administering of drugs, either of a poisonous or detrimental nature from a container, when handling the same either carelessly, or in the dark, thus assuring 30 safety in such handling of the container when a person is unfamiliar with the contents thereof.

A further object of the invention is the provision of a device of this character 35 wherein the same can be conveniently attached to and removed from a container, and when attached, will give ornamental 40 thereto, as well as assuring safety in the handling of the container.

45 A still further object of the invention is the provision of a device of this character which possesses simplicity in construction, durability, reliability, and efficiency in its purpose, and also one which is inexpensive in manufacture.

With these and other objects in view, the invention consists in the construction, combination, and arrangement of parts, as will be hereinafter fully described, illustrated in 50 the accompanying drawing, and pointed out in the claim hereunto appended.

In the accompanying drawing:

Figure 1 is a fragmentary side elevation of a bottle showing the device constructed 55 in accordance with the invention applied.

Fig. 2 is a fragmentary vertical longitudinal sectional view through the bottle and device.

Fig. 3 is a plan view of the neck band for the bottle.

Fig. 4 is a plan view of the stopper cap, with the anchoring pin removed.

Similar reference characters indicate corresponding parts throughout the several views in the drawing.

Referring to the drawing in detail, A designates a portion of the body of a bottle having the usual neck B, its mouth end being closed through the medium of a stopper or cork C, as usual, which is removable therefrom for the dispensing of the contents of 70 the bottle.

Carried by the outer end of the cork, is an indicator cap, comprising a semi-spherical body 5, preferably made from glass, although the same may be made from any other suitable material, and on the spherical surface of said body 5, are formed closely arranged rows of pointed teeth, or spurs 8, which serve to prick the finger or fingers 80 of a person, when attempting to extract the stopper or cork C from the mouth end of the neck B of the bottle, and thus indicating the particular nature of the contents of the bottle, should the same be of a poisonous or 85 dangerous quality.

Provided centrally in the body 5, is a bore or hole 9, through which is passed an anchoring pin 10, formed at its outer end with an eye 11, while the inner end portion of the 90 pin is spurred or toothed as at 12, so that on penetrating the stopper or cork C, the pin will be retained or anchored therein for the fastening of the stopper or cork C and the body of the cap 5 together, as will be 95 clearly apparent.

Embracing the neck B of the bottle A, exteriorly thereof, is a band 13, preferably made from metal, having the required flexibility to permit the training of the same 100 about the neck B of said bottle, one end of the band being formed with a loop or eye extension 14, while the other end of the band is provided with a bendable tongue 15, adapted to be inserted in the loop or eye 14, 105 and bent on itself for the fastening of the band in place upon the bottle neck.

The band 13 on the outer face thereof, is corrugated or cut to form rows of pointed teeth 16, which serve to prick the hand of a 110

person when grasping the bottle at the neck thereof, thereby indicating the nature of the contents of such bottle.

Loosely engaged on the tongue 15 of the band 13, when fastened in the loop or eye end 14, is a ring 17, to which is connected the retaining chain 18, the other end of the latter being also loosely connected to the eye 11 of the anchoring pin 10, and this chain 10 serves the purpose of preventing the accidental loss of the stopper or cork C with the cap body 5 thereon, and its anchoring pin.

When the stopper or cork C becomes unfit for use, the pin 10 can be readily removed therefrom, so that the cap can be fastened to a new stopper or cork, and by the reason of the particular construction of the band 13, it is adaptable for different sizes of necks or bottles, so that the device can be 20 used on bottles of different sizes, and also the cap of said device can be anchored upon different sizes of corks or stoppers.

From the foregoing, it is thought that the

construction and manner of use of the invention will be clearly understood, and 25 therefore, a more extended explanation has been omitted.

What is claimed is:—

A device of the character described comprising a cap formed with a toothed outer 30 surface and adapted to be engaged on a cork, an anchoring pin passed through the cap and adapted to engage the cork, an eye formed on the outer end of the pin, an attaching chain connected to the eye, a ring 35 on the outer end of the chain, a flexible band having a toothed outer surface adapted to be engaged about a bottle neck and having a slot formed in one end thereof, and a bendable tongue continuing from the band and engaging the ring and the slot for holding the band and the cap against accidental displacement.

In testimony whereof I affix my signature.

HOMER NEFF TYSON.
